ENVELOPE

Warren R. Leas, Wyoming, Pa., assignor of one-third to Samuel Shannon, Forty Fort, Pa., and one-third to Frederick A. Hopper, Wyoming, Pa.

Application April 6, 1931. Serial No. 528,109

2 Claims. (Cl. 229—82)

This invention relates to new and useful improvements in paper receptacles and more particularly to a novel letter envelope.

The principal object of this invention is to provide an envelope with means whereby the interior of the envelope or the letter sheet will be marked in the event the envelope has been tampered with.

Another important object of the invention is to provide an envelope with means rendering the opening thereof difficult without resulting in the creation of some token making it apparent that the envelope has been tampered with.

Other important objects and advantages of the invention will become apparent to the reader of the following specification.

In the drawings:—

Figure 1 represents a rear side elevational view of one form of the envelope sealed.

Fig. 2 represents a rear side elevational view of the form of the invention shown in Fig. 1 with the upper flap in open position.

Fig. 3 represents a top plan view of the envelope sheet before it is assembled.

Fig. 4 represents a cross sectional view taken substantially on the line 4—4 of Fig. 1.

Fig. 5 represents a fragmentary outside elevational view of the top flap of the form shown in Fig. 2.

Fig. 6 represents a side elevational view of a folded letter sheet showing the marks produced by the dye paper.

Fig. 7 represents a fragmentary sectional view taken substantially on the line 7—7 of Fig. 3.

Fig. 8 represents a rear side elevational view of the second form of the invention.

Fig. 9 represents a rear elevational view of the form of the invention shown in Fig. 8 with the top flaps in open position.

Fig. 10 represents a plan view of the envelope sheet before assemblage.

Fig. 11 represents a cross sectional view taken substantially on the line 11—11 of Fig. 8.

Fig. 12 represents a rear elevational view of the third form of the invention.

Fig. 13 represents a rear side elevational view of the form of the invention shown in Fig. 12 with the top flap in open position.

Fig. 14 represents a top plan view of the envelope sheet of the form shown in Fig. 12 before being assembled.

Fig. 15 represents a rear side elevational view of a fourth modification of the invention.

Fig. 16 represents a rear side elevational view of the envelope shown in Fig. 15 with the top in open position.

Fig. 17 represents a top plan view of the envelope sheet of the form shown in Fig. 15, before assembled.

Fig. 18 represents a rear side elevational view of the fifth form of the invention.

Fig. 19 represents a rear side elevational view of the form of the invention shown in Fig. 18 with the top flap in open position.

Fig. 20 represents a top plan view of the envelope sheet of the form shown in Fig. 18 before assembled.

Fig. 21 represents a fragmentary top plan view of a portion of any one of the envelopes, showing the glued portion to which the dye paper is adhered.

Fig. 22 represents a fragmentary rear side elevational view of particularly the invention shown in Figs. 8, 12 and 18, disclosing information that may be adopted.

Fig. 23 represents a fixed modification of the invention, the change being in the flap.

Fig. 24 represents a fragmentary plan view of any one of the envelopes showing a circular dye paper in place of the rectangular forms shown in the other views.

Fig. 25 represents a fragmentary sectional view disclosing a modification of the die paper.

Referring to the drawings wherein like numerals designate like parts, it can be seen that in each form of the invention the envelope consists of a sheet formed with the front section 5, the end flaps 6—6, and the top and bottom flaps 7 and 8 respectively.

In each of the forms of the invention, at least one marking unit is provided and these units are represented in different forms in Figs. 7, 21, 24 and 25. While the particular shape of the opening in the envelope sheet is immaterial, Fig. 21 discloses a circular opening 9 located between a pair of elongated adhesive coatings 10—10 and the rectangular shaped dye paper 11 is adhered at its ends to the envelope sheet by these coatings.

Fig. 24 shows the circular opening 9, however, the envelope sheet and its opening 9 is coated with adhesive, whereby the circular dye paper 12 is secured thereto.

Another form of the marking unit is disclosed in Fig. 25 wherein a sheet of thin white transparent material 13 is secured to the outer side of the die paper 14 so that the dye paper will be substantially visible, yet readily activated by hot water, steam or the like to the material 13. For the purpose of facilitating the following description of the market units, it will be generally referred to by numeral 15, and it is to be under-

stood that any one of the forms of the marking unit can be employed in lieu of the particular form represented and furthermore, various other modifications of the marking unit can be adopted within the scope of the claims appended. Furthermore, it is preferable that the material 13 be of a moisture-proof material such as cellophane.

Referring now to Fig. 1, it can be seen that this is the first form of the invention and Fig. 3 shows that both the upper and lower flaps 7 and 8 are provided with a marking unit. As is shown in Fig. 2, when the flaps 6-6 are bent inwardly, they terminate in spaced relation to each other, so that dye from the markings unit 15 on the lower flap 8 can reach the letter sheet.

The free edge portion of the lower flap 8 is provided with an adhesive 16 for cohesion with the flaps 6 to assume the position shown in Fig. 2. The lower flap 8 is provided with a slot 17 for receiving the tab 18 on the upper flap 7. The flap 8 at the intermediate portion of the slot 7 is provided with a notch 13. The aforementioned tab 18 has its entire inner surface provided with an adhesive coating which merges with the adhesive margin 20 on the edge portion of the upper flap 7. The tab 18 has an opening 21 therethrough and a strip of adhesive coating 22 on the outer side thereof.

It will now be observed that the tab 18 is inserted downwardly through the slot 17 so that the opening 27 registers with the opening 9 of the lower flap 8. The adhesive coating on the inside of the tab 18 will adhere to the end flaps 6-6, while the strip of adhesive 22 will adhere to the inner side of the lower flap 8. The marking unit 15 of the upper flap 7 will register with the space between the curved corners 22 of the end flaps 6-6.

Fig. 8 shows a second form of the invention wherein the upper flap 7 is provided with the slot 17' and notch 19', adjacent to which is located a marking unit 15. The inner side of the tab 21' is provided with an adhesive coating 24 as is the space surrounding the slot 17'. This adhesive coating merges with the marginal adhesive portions 20'. The lower flap 8 has its apex portion provided with a pair of parallel inwardly disposed slits 23-23 for defining a tongue 24 having an opening 25 therein. The corners of the flaps 8 adjacent the top 24 are cut away as at 26. The edge portion of the flap 8 including the edge portion along the slots 23-23 is provided with an adhesive coating 27, this being exclusive of the tongue 24 which has substantially one-half portion of its outer side provided with an adhesive coating 28. (See Fig. 9).

The upper corner portions of the flaps 6-6 are notched out as at 29 to provide an opening registerable with the opening 25 and opening 9 of the marking unit 15. It can now be seen that the tab 21' is insertible under the tongue 24, while the tongue 24 extends over the tab 21 and through the slot 17' to pass under the marking unit 15 and to cohere the same solidly to the top flap 7, with the opening therein registering with the opening 9 of the marking unit 15.

Fig. 12 shows a third form of the invention which is very similar to the form shown in Fig. 8, excepting that the ends of the flaps 6-6 are provided with notches 30, which when the flaps 6-6 are brought together, forms an opening registering with the opening 31 in the tab 21a. The slot 17' and notch 19' are provided in this

form with the marking units 15 located adjacent thereto.

Located adjacent to the tongue 24 is a second marking unit 15. The envelope is constructed otherwise identically with the form shown in Fig. 8. It can be seen, that when the flaps 6-6 are folded inwardly, and the lower flap is folded against the same, the tab 21a is inserted under the tongue 24, while the tongue 24 is disposed over the tab and through the slot 17'. The opening 31 in the tab 21a registers with the opening 9, of the marking unit 15 so that the dye paper thereof will be exposed to the letter sheet. The adhesive side 28 of the tongue 24 will of course cohere with the inner side of the top flap 8 so as to firmly secure the upper marking units against the upper flaps, with the openings 25 in the tongue registering with the opening 9 of the uppermarking units.

The fourth form of the invention is shown in Fig. 15. In this form of the invention, the upper flap 7 is provided with a small ear 31 on each side of the tab 18' and is provided with the opening 21'. Otherwise, this envelope is constructed in substantially the same manner as the form shown in Fig. 1, with the exception of the notches 32-32 in the ends of the flaps 6-6, which serve to provide an opening in the present case, where the ends of the flaps 6-6 terminate in close relation, these notches not being necessary in the form shown in Fig. 1 because the flaps terminate sufficient apart. With the envelope shown in Fig. 15 assembled in the same manner as the envelope in Fig. 1, the ears 31-31 adhere against the outer side of the lower flap 8 so as to make it considerably difficult to insert an instrument.

Fig. 18 discloses the fifth form of the invention which is substantially like the form shown in Fig. 12, with the exception that the flaps 6-6 terminate sufficiently apart to make the notches 30 unnecessary. Furthermore, the form of the invention shown in Fig. 18 and more clearly shown in Fig. 20, does not have the cut-away corners 26 as in the form of the invention shown in Fig. 8 and more specifically represented in Fig. 10, but has the blunt end portions 32-32 at the opposite sides of the tongue 24.

The envelope shown in Fig. 18 has assembled in the same manner as the envelope in Fig. 12, however, it will be observed that across the blunt end portions 32-32, a greater adhesive surface is presented.

Fig. 23 shows a modification of the upper flap 7 such as is shown in Figs. 10, 14 and 20, wherein the notch 19' has its edge portion provided with a plurality of indentations 33. Fig. 22 shows that considerable information 34 can be stamped on the tongue 24 and that certain indicative data can be located adjacent the marking units 15.

By way of illustration, take for instance the envelope shown in Fig. 1. A knife or some other instrument is inserted under the flap 7 in an attempt to open the envelope with the least possible damage thereto. The knife will engage the dye paper of the upper marking unit and will detach the same from the flap so that it will disappear from the opening 9. Obviously, no matter how ingeniously the envelope is reconstructed, the dye paper will be absent from its proper location, and the receiver of the envelope will know that the same has been tampered with.

When the ears 31-31 in the form of the invention shown in Fig. 15 are employed, the same make the insertion of an instrument much more

difficult and obviously the detaching of either one of these ears 31 is sufficient evidence that the envelope has been handled by an unauthorized person.

5 If in the event the wrongdoer attempts to unseal the envelope by steam, a wet blotter or the use of water or in any form, the dye will run from the marking units 15 directly onto the letter sheet and will mark the letter sheet in the 10 manner substantially shown in Fig. 6, wherein numeral 35 represents the letter sheet and 36 the blocks of dye thereon, which indicate that before the sendee received the envelope, some one had attempted to open the same by the application of moisture in some form sufficient to cause the dye to run from the dye paper from the one or more marking units employed.

15 It is to be understood that while the foregoing specification sets forth a limited number of forms 20 of the invention, numerous other forms can be produced in addition to the foregoing within the scope of the appended claims, and while the foregoing description has been specific, it is to be understood that numerous changes in shape, 25 size and materials may be resorted to without departing from the spirit and scope of the invention as claimed hereinafter.

Having thus described my invention, what I claim as new is:—

1. An envelope comprising a front side, a back side, a closure flap, said flap being provided with a tongue, said back side of the envelope being provided with a slot through which the tongue can be inserted and secured, the edge portion of the back side at the slot exposed when the tongue is inserted having a notch therein which will expose a jointure of the tongue and flap in the event the tongue has been severed from the flap and replaced. 80

2. An envelope comprising a front side, a back side, a closure flap, said flap being provided with a tongue, said back side being provided with a slot for receiving the tongue, said flap being provided with a pair of ears, one ear on each side of the tongue at the point where the tongue joins the flap, said ears projecting in the direction of the tongue, said ears and flap being gummed on one side to adhere the same to the back side of the envelope so that the said ears can be secured in substantial alignment with the slot, one being located at each end of the slot. 85 90 95
